UNITED STATES PATENT OFFICE.

DAVID O'NEILL, OF WOODSIDE, NEW YORK.

WINDOW-SCREEN GUIDE.

1,259,549.

Specification of Letters Patent. Patented Mar. 19, 1918.

Application filed May 9, 1917. Serial No. 167,486.

To all whom it may concern:

Be it known that I, DAVID O'NEILL, a citizen of the United States, residing at Woodside, L. I., in the county of Queens 5 and State of New York, have invented certain new and useful Improvements in Window-Screen Guides; and I do hereby declare the following to be a full, clear, and exact description of the invention, such as will 10 enable others skilled in the art to which it appertains to make and use the same.

My invention relates to improvements in window screens of that type forming the subject matter of my Patent Number 15 1,240,768, Sept. 18, 1917, and its primary object is to provide a means adapted to prevent the side edges of the screen material from being pulled or withdrawn from the guides, the means comprehending a structure, which will not interfere with the free 20 rolling upon or off of the screen upon the roller.

A still further object of my invention is to provide a pair of novel guides adapted to 25 be secured in the guide ways of a window frame, which have their lower ends communicating with the casing having the screen rolled therein, the lower ends of the guides communicating with the casing to permit the 30 screen to be unwound from the roller and pass into the guides to be held therein when in fully raised position.

A still further object of my invention is to provide the opposite side edges of the 35 screen material with flexible hinged strips or sides and to provide the guides with novel means, which are adapted to engage the strips and turn them at an angle with relation to the screen, thus preventing the screen 40 from being pulled or withdrawn from the guides when the screen is raised.

A still further object of this invention is to provide the guides with a novel block, which has an inclined face, the lower end 45 of the block being inclined in an opposite direction to engage the screen on its initial movement in the guides to turn the hinged strips at an angle to the screen body, thus preventing the withdrawal from the guides 50 when the screen is in fully raised position.

A still further object of this invention is to provide a device of this character, which will be simple, practical and comparatively inexpensive in construction, and one that 55 can be manufactured and sold at a low cost.

With these and other objects in view, the

invention consists in the novel combination and arrangement of parts such as will be hereinafter more fully described and set forth in the claims hereto appended. 60

In the drawings:

Figure 1 is a front elevation of a window illustrating a rolling window screen applied thereto and which is constructed in accordance with my invention, 65

Fig. 2 is a vertical sectional view of the same,

Fig. 3 is a fragmentary vertical sectional view illustrating the manner in which the guides are connected to the roller casing, 70

Fig. 4 is a transverse sectional view taken on the line 4-4 of Fig. 2,

Fig. 5 is a transverse sectional view taken through one of the guides, illustrating the manner in which the screen is held against 75 withdrawal therefrom,

Fig. 6 is a bottom plan view of one of the guides illustrating the manner in which the hinged strip of the screen is turned at an angle to the body, 80

Fig. 7 is a perspective view of the lower end of the guiding block,

Fig. 8 is a transverse sectional view taken through the lower portion of one of the guides to illustrate the initial position of the 85 screen within the guides prior to it being fully placed within the guides.

Fig. 9 is a front elevation of the lower portion of the guide blocks,

Fig. 10 is an end elevation of the same, 90

Fig. 11 is a fragmentary front elevation of the screen illustrating the manner in which the strip is hinged to the side edges.

Like numerals of reference designate corresponding parts in all the figures of the 95 drawings;

Referring to the drawings, the numeral 1 designates a window frame having the usual sill 2 and the vertical guide ways 3 and 4, in which are slidably mounted upper and 100 lower window sashes 5 and 6. The foregoing description relates to a well known construction of a window and to which my invention is applied. My invention relates to my patented application, a brief description 105 of which is as follows:

An elongated casing 7 is provided with a curved top wall 8, which is provided with a longitudinally extending slot adjacent the rear wall thereof, as at 9 forming an exit or 110 opening to the casing. The casing 7 has its ends closed by the end walls 10, and each

of which are apertured for the purpose of rotatably supporting a roller 11.

My improved construction is applied to the above typed description and includes a 5 pair of vertical guides 12, each of which is formed of a single piece of suitable material. The guides 12 have their lower ends flared and adapted to rest on each end of the casing 7 adjacent the slot 9 for receiving the 10 side edges of a screen 13, which is wound upon the roller 11 located within the casing and extends out of the casing by the way of the slot 9.

The guides 12 are substantially U-shaped 15 in cross section and have one of their arm portions inclined inwardly as at 14 to provide a retaining flange, the terminal of the retaining flange is bent outwardly as at 15 and is arranged parallel with the arms 16 20 of the guides and in spaced relation thereto to provide a substantially vertical slot for receiving the side edges of the screen 13 when moving into the guides when passing from or off of the roller 11.

The lower end of the arm 16 is flared outwardly as at 17 and the lower end of the member 15 is slotted and bent upwardly as at 19 to leave the lower ends of the guides 25 fully open as at 20 and shown in Fig. 3 to permit the free sliding movement of the screen 13 up into the guides 12.

The guides 12 are provided adjacent their upper ends on the outer side of the arms 16 with laterally extending lugs 21 to which is 30 pivotally secured the locking arm 22, which has a cam working surface 23, which is adapted to engage one of the walls of the 35 guide way 3, thus forcing the other arm of the guides 12 into engagement with the other wall, thereby locking the guides 12 vertically within the guide way 3, as clearly shown in Figs. 1 and 2.

A guide block 24 is substantially triangular in cross section and is slidably arranged 40 in the guides 12 and has one vertical side edge extended as at 26 to provide a relatively straight wall 27, thus positioning the inclined face 28 in parallel relation with the retaining flange 14, and in spaced relation 45 thereto.

The lower end of the guide block 24 is beveled and inclined in a direction opposite to the inclined surface 28, as at 29 and tapers into an extension 30, and is adapted to receive the side edges of the screen on its initial movement into the guides, the purpose 50 of which will be hereinafter more fully described.

The free end of the screen 13 is secured to 55 the usual attaching strip used in my patented construction and designated 31, which is secured to the sash 6 by clumps 32, and it is secured to the free end of the screen by the pins 33, thus it can be seen that when the 60 sash 6 is raised that the screen will be moved

upwardly into the open space normally closed by the sash 6 when down and the side edges of the screen 13 will enter into vertically extending guides 12 and be retained therein and against withdrawal therefrom by a novel means, which will be herein-after more fully described.

The screen 13 has hingedly connected to the side edges a flexible strip 34, which is hingedly connected to the side edges as at 75 35 in any suitable manner, it being shown here as a substantially serpentine selvage edge hingedly connected to the sides of the screen 13 by a single length of wire 36, which is woven into the material 13 and provided with loops 37, which engage the portions of the strip 34 to hingedly connect it to the side edges of the screen 13.

The hinged connection of the strip 34 with the side edges of the screen 13 permits 85 this strip to be moved in any angled position entering into the guides 12, thereby when turned into the angled position shown in Fig. 5, it is fully up into the guides 12 and is held against withdrawal therefrom by 90 a retaining flange 14 and the angular formation of the strip 34 with relation to the screen 13.

It is to be understood that the strip 34 may be any form or shape and hingedly connected to the side edges of the screen that upon the initial movement of the same into the guides, it will engage the side 29 of the block 24 and upon further movement up in the guides 12, it will be turned in the angle 100 illustrated in Fig. 5, due to the inclination of the face 28 of the block 24, thereby retaining the screen in the guides when in fully raised position within the guides.

It is also to be noted that the hinged connection of the strip 34 to the screen 13 prevents movement of the screen from the guides, thereby preventing access to the interior of the room or the like by insects from the exterior.

In use, the location of the lower ends of the guides is directly over the slot 9 in the casing 7, thereby when the sash 6 is raised, the screen will be unwound from the roller 11, the upper end of the screen entering into 115 and through the slot 9 of the casing and the side edges of the screen entering the guides 12 and the flexible strip 34 engaging the face 28 and the box 29, whereby further movement into the guides 12, the flexible 120 strip 34 will be bent angularly with relation to the body 13, as shown in Fig. 5, thus positioning the member 34 or flexible strip 34 behind the retaining flange 14 of the casings 125 or guides 12 and thereby prevent the screen 125 from being withdrawn bodily from the guides until rewound upon the roller 11.

What is claimed is:

1. A screen, a strip hingedly connected to the side edges of the screen, guides, flanges 130

- carried by the guides, and means within the guides for engaging the strip to bend it at an inclination to the screen to prevent the withdrawal of the screen from the guides, as and for the purpose specified.
2. A screen, a flexible strip hingedly connected to the side edges of the screen, guides, a retaining flange carried by the guides, and means located in the guides and in spaced relation to the retaining flange to bend the strip at an angle to the screen when moved into the guides to prevent the withdrawal of the screen from the guides, as and for the purpose specified.
3. A rolling window screen including a screen body, a flexible strip hingedly connected to the side edges of said screen body, guides, an inclined retaining flange carried by said guides, and means located within the guides and in spaced relation to the retaining flange to bend the strip at an angle to the body of the screen when moved into the guides to prevent the withdrawal of the screen from the guides.
4. A rolling window screen comprising a screen, a flexible strip hingedly connected to the marginal side edges of the screen, guides, a retaining flange carried by said guides, and a block located within the guides and having an inclined face, which is arranged in spaced relation to the retaining flange, and said block adapted to engage the strip of the screen on its initial movement into the guides to bend the strip at an angle with relation to the screen to locate the same behind the retaining flange of the guides to prevent the withdrawal of the screen from the guides.
5. A rolling window screen of the class described including a screen, a strip hingedly secured to the marginal side edges of the screen, guides substantially U-shaped in cross section, one arm of the guides inclined inwardly to define a retaining flange, the inner terminal of the retaining flange bent outwardly in spaced relation to the other arm of the guides to provide a slot to permit the screen body to move freely into the guides, and a block located within the guides and having an inclined face arranged in parallel spaced relation with the retaining flange of the guides, the lower portion of the block being beveled and inclined in a direction opposite to the inclination of the other face to permit the insertion of the hinged strips therein, and to bend the strip at an inclination to the body of the screen to locate the same behind the retaining flanges of the guides to prevent the withdrawal of the screen from the guides, as and for the purpose specified.
6. A rolling window screen comprising a screen body, a strip hingedly connected to the marginal side edges of the body, guides, blocks arranged in the guides, a flange carried by the guides and in spaced relation to the blocks, said blocks adapted to move the flexible strips of the screen to an angled position with relation to the body of the screen when moved into the guides to prevent withdrawal of the screen from the guides, as and for the purpose specified.
7. A rolling window screen comprising a screen body having opposite side marginal edges provided with hinged strips, beveled guides, said guides being substantially U-shaped in cross section and having one of its arms inclined inwardly to provide a retaining flange, the inner end of the retaining flange bent outwardly and in spaced parallel relation with the other arm of the guides, a substantially triangular shaped block arranged in said guides, having one of its inclined faces in spaced parallel relation with the retaining flange, the lower edge of said block having its face beveled and inclined in a direction opposite to the inclination of the face which is parallel with the flange, said inclined faces of the block adapted to bend the hinged strips of the screen body at an angle to the body when the screen is moved into the guides, as and for the purpose specified.
8. A screen including a body, a transversely flexible strip hingedly connected to the side edges of the body, guides, means located in the guides for moving the strips at various angled positions with relation to the body, as the side edges are moved up into the guides.

In testimony whereof I affix my signature in presence of two witnesses.

DAVID O'NEILL.
